UNITED STATES PATENT OFFICE.

FERDINAND GROYEN, OF COLOGNE, GERMANY, ASSIGNOR TO THE FIRM OF GROYEN AND RICHTMANN, OF COLOGNE, GERMANY.

TYPE-WRITING MACHINE FOR PRINTING NOTES.

1,074,858.

Specification of Letters Patent.

Patented Oct. 7, 1913.

Application filed June 11, 1912. Serial No. 703,030.

To all whom it may concern:

Be it known that I, FERDINAND GROYEN, a citizen of the German Empire, residing at Cologne, in the Kingdom of Prussia, Germany, have invented certain new and useful Improvements in Type-Writing Machines for Printing Notes; and I do hereby declare the following to be a full, clear, and exact description of the invention, such as will enable others skilled in the art to which it appertains to make and use the same.

My invention relates to improvements in typewriting machines for printing notes, and more particularly to typewriting machines in which the platen is adapted to be rotated according to the line or space of the staff to be printed upon by means of a toothed gearing which is adapted to be coupled with the platen so as to transmit rotary movement thereto but does not take part in its longitudinal or letter spacing movement, and the object of the improvements is to provide a machine of this class in which the gear wheel may be disconnected 25 from the platen, so that when printing ordinary characters the gear wheel is not carried along by the rotation of the platen.

With this object in view my invention consists in providing a coupling member between the toothed gear wheel and the platen. When the said platen is connected with the toothed gear wheel, and the latter is rotated, such rotation is imparted to the platen in any position of the latter. If it is desired 35 to print ordinary characters with the typewriting machine, the platen and gear wheel are disconnected from each other, so that the platen can be rotated independently of the gear wheel.

A further feature of my invention relates to the mechanism for rotating the gear wheel which is adapted to be connected with the platen for printing notes. This mechanism consists of a rock shaft having a 45 toothed sector and a lever keyed thereto. The sector is in engagement with the gear wheel, and the lever is adapted to be rocked along a graduated segment. The whole mechanism is mounted on a slide which is 50 adapted to be shifted toward and away from the gear wheel, so that the latter can be thrown out of engagement with the toothed sector.

For the purpose of explaining the invention an example embodying the same has

been shown in the accompanying drawings in which the same letters of reference have been used in all the views to indicate corresponding parts.

In said drawings—Figure 1, is a partial plan view of a typewriting machine showing the parts embodying my invention, Fig. 2, is a side view thereof, Fig. 3, is a longitudinal section of the platen, Fig. 4, is a cross-section of the platen taken on the line A—B 65 of Fig. 3, and Fig. 5, is a cross-section taken on the line C—D of Fig. 3.

Referring to the example illustrated in the drawings, on the base plate 1 of the typewriting machine a platen 6 is mounted 70 in suitable bearings so as to be longitudinally shiftable thereon for letter spacing. The platen is adapted to be rotated for line spacing by any known or preferred means not shown. At one end of the platen a 75 toothed gear wheel 3 is mounted in brackets 2, and the shaft 3' of the gear wheel is adapted to be coupled to a shaft 5 by a clutch which in the example illustrated consists of a set screw 4. The shaft 5 extends 80 into the hollow of the platen 6 which as shown consists of a steel cylinder and a lining of rubber. The steel cylinder is formed with a pair of longitudinal ribs 7 providing guide ways for a notched cross-piece 8 secured to the end of the shaft 5. When the toothed gear wheel 3 and the shaft 5 are coupled with each other by means 85 of the set screw 4 rotation of the wheel 3 is transmitted to the platen. When printing 90 ordinary characters, the set screw is loosened, so that the wheel 3 does not take part in the rotation of the platen imparted thereto by the usual line spacing mechanism.

The gear wheel 3 is adapted to be rotated 95 by means of a toothed sector 9 which is secured to a shaft 10 rotatably mounted in brackets 10' of a slide plate 11. The latter is adapted to be shifted toward and away from the platen and with the sector 9 into 100 or out of engagement with the gear wheel 3. In the example illustrated in the drawings such movement is imparted to the slide plate 11 by means of a rocking lever 19 having a slotted transverse arm 12 engaging a pin 13 secured to the slide plate. The arm 12 is arranged at an angle to the lever 19, so that when rocking the lever sidewise the slide plate 11 is shifted toward or away 105 from the platen. At the end opposite to 110

the sector 9 the shaft 10 carries a lever 14 formed with a hand piece 15 adapted to be shifted along a circular scale 16. As shown in Fig. 1, the said scale shows the lines and spaces and the added lines and spaces of the staff. The lever 14 is equipped with a laterally projecting thumb nut 17 by means of which it can readily be shifted. To lock the lever in set position a toothed sector 18 is provided which is adapted to be engaged by a spring actuated edge provided on the lever 14. When rocking the lever 14 the said edge is automatically lifted out of engagement with the toothed sector, which may be done for example by rotating the thumb nut 17.

The mechanism for rotating the platen, and the type keys and their operating mechanism may have any known or preferred construction. Such means are known in the art and need no detailed description.

While in describing the invention reference has been made to a particular example embodying the same, I wish it to be understood that my invention is not limited to the construction shown in the drawings, and that various changes may be made in the general arrangement and construction of the parts.

30 I claim herein as my invention:

1. In a typewriting machine for printing notes, the combination with the platen, of a shaft permitting longitudinal movement of the platen and adapted to transmit rotary movement thereto, a toothed gear wheel, a clutch mechanism intermediate said shaft and gear wheel, means to rotate said toothed gear wheel, and a slide carrying said rotating means and adapted to shift the same into or out of engagement with said gear wheel.

2. In a typewriting machine for printing notes, the combination with the platen, of a shaft directly connected with said platen and adapted to permit longitudinal movement thereof and to transmit rotary movement thereto, a toothed gear wheel, mechanism adapted to rotate said gear wheel for setting the platen in positions for printing on different lines and spaces of the staff, and a slide carrying said rotating means and adapted to shift the same into or out of engagement with said gear wheel.

3. In a typewriting machine for printing notes, the combination with the platen, of a shaft permitting longitudinal movement of the platen and adapted to transmit rotary movement thereto, a toothed gear wheel, a toothed sector engaging said gear wheel, means to rock said sector, and a slide carrying the sector and rocking means and adapted to throw the sector into or out of engagement with the gear wheel.

4. In a typewriting machine for printing notes, the combination with the platen, of a shaft permitting longitudinal movement of the platen and adapted to transmit rotary movement thereto, a toothed gear wheel, a toothed sector engaging said gear wheel, a rock shaft carrying said sector, a lever fixed to said rock shaft for rocking the same, a curved member adjacent said rocking lever and having a scale indicating the lines and spaces of the shaft, and means for holding said lever in the position to which it is moved.

In testimony whereof I hereunto affix my signature in the presence of two witnesses.

FERDINAND GROYEN.

Witnesses:

LOUIS VANDORY,
BESSIE F. DUNLAP.
